CARL E. L. LIPMAN, OF BELOIT, WISCONSIN, ASSIGNOR TO THE LIPMAN MANUFACTURING COMPANY, OF BELOIT, WISCONSIN, A CORPORATION OF WISCONSIN.

AIR-PUMP.

1,092,495.

Specification of Letters Patent.

Patented Apr. 7, 1914.

Application filed May 19, 1913. Serial No. 768,580.

To all whom it may concern:

Be it known that I, CARL E. L. LIPMAN, a citizen of the United States, residing at Beloit, in the county of Rock and the State of Wisconsin, have invented certain new and useful Improvements in Air-Pumps, of which the following is a specification.

This invention relates to air pumps and has for its object the construction of a valve head for the pump in which a novel type of separate valves for each cylinder are "built in" and entirely carried by the head, so that in the manufacture of the pump the valve head and mechanism may be made up entirely separate from the rest of the pump and assembled in working condition before being placed upon the pump.

The further object is to provide a cap to cover entirely the valve mechanism carried by the head so that same will be protected from any foreign matter coming in contact with the head of the pump, and to construct said cap with sides lying in close proximity with the sides of the pump so as to allow a narrow passage therebetween through which air may be drawn to the intake valves.

In the accompanying drawings: Figure 1 is a side view of a pump with my improved valve head and mechanism applied thereto, the upper portion thereof being shown in section as taken on the line 1—1 of Fig. 2. Fig. 2 is a plan section taken on the line 2—2 of Fig. 1. Fig. 3 is a vertical transverse section taken on the line 3—3 of Fig. 2.

The air pump here disclosed is especially adapted for use in connection with automobiles in furnishing air for self starting systems, filling tires, etc., and for such uses as a small type of multi-cylinder pump is required.

The pump comprises a crank case 4, cylinder casing 5 and the several operative parts such as pistons, crank-shaft, etc., co-operating with same to produce an operative pump. The top of the casing 5 is ground off flush and a head 6 is screwed thereupon by screws 7. This head adapted to carry the valve mechanism, forms the head for the cylinders and carries a separate intake and exhaust valve for each cylinder in such a manner as to allow the pistons to be moved in their up stroke, close to the head 6 to discharge a maximum amount of air from the cylinders. The intake valves are of the lift puppet valve type, their stems being

guided in vertical supports 9 formed with the head 6; and the valves being yieldingly held upon their seats by coiled springs 10 interposed between collars 11 mounted upon the valve stems and the intake port walls 12 which have intake ports 13 therein. One of these puppet valves is positioned above each cylinder and it will be noticed that upon the upstroke (when said valves are inoperative) that the valve is flush with the cylinder top. An exhaust or discharge passage 14 leads longitudinally across the cylinder heads having a communicating port 15 with each cylinder. The discharge valves at each of said ports are in the form of ball lift or check valves with balls 16 seated in ports 15 and held yieldingly in position by springs 17 mounted upon the balls, the springs being held in position by the recessed caps 18 which are screwed into the casing of passage 14. The end 19 of said passage is adapted to form a connecting means to which a lead of pipe may be connected to conduct the air compressed by the pump to any desired point of use. A cap 20 has lugs 21 depending from its top and resting upon the discharge passage casing, screws 22 through said lugs being used to hold the cap fixed upon the pump head, and the cap having side walls 23 depending from its top, said walls being positioned close to the sides of the pump and valve head, but allowing an air passage 24 intermediate the cap and pump, and said walls extending down over the pump head to such a distance that said air passage about the pump head has a depth of a sufficient degree to keep foreign particles coming in contact with the pump head from being drawn upward through the passages as fresh air is being drawn to the intake valves.

In the operation of the pump, when the pistons are reciprocated, on the down stroke thereof air will be drawn through the intake valves 8 by way of the passages 24 and ports 13, to the cylinders, the ball valves being held seated by the suction and also by their springs 17, and upon the up strokes of the pistons the air within the cylinders will be forced out through ports 15 and passage 14, at a pressure to be utilized for various purposes. It will be seen that in this valve construction a tensional spring force is always upon the valves to hold them closed and also when the pump is in operation ad-

ditional force created through the suction and pressure strokes of the pistons assists in further holding the exhaust and intake valves closed.

5 By constructing the valves as above disclosed a very simple and efficient construction is resultant, and which enables all intricate working operations upon the valve construction of the pump, during the manufacture thereof, to be performed entirely upon the valve head, also allowing the valve mechanism to be assembled in an operative condition before being applied to the pump.

10 To protect the valve mechanism and to guard against any particles of foreign matter falling or coming in contact with the pump head while the pump is in operation, from being drawn into the valve mechanism, I utilize my novel form of pump cap which 15 entirely incloses the valve mechanism and provides guarded air passages leading to the intake valves. It will be seen that this construction not only does away with separate casings for intake valves and screens for 20 keeping dirt from being drawn through same, but also affords an efficient guard for the entire pump head and mechanism.

25 I claim as my invention—

1. In an air pump, the combination with 30 a cylinder and piston therefor, of a head forming a top for the cylinder, an air intake and exhaust valve located in the head, the intake valve drawing from the atmosphere and the exhaust valve having a discharge passage, and a cap inclosing said 35 valves and carried by the head, the cap leaving an opening intermediate the pump head and cap wherethrough air may pass to said intake valve.

2. In an air pump, the combination with a 40 cylinder and piston therefor, of valve mechanism located on the head of the cylinder including an air intake valve adapted to draw air from the atmosphere, and a casing covering said valve mechanism and having side 45 walls disposed adjacent the sides of said valve mechanism, said side walls forming with the valve mechanism an air passage through which air may pass to said intake valve.

3. In an air pump, the combination with a cylinder and piston therefor, of valve mechanism located on the head of the cylinder including an air intake valve adapted to draw air from the atmosphere, and a casing covering said valve mechanism and pump head, the casing having depending side walls positioned adjacent the sides of the pump head and forming with said head, an air passage through which air may pass 60 to said intake valve.

4. In an air pump the combination with a cylinder and piston therefor, of valve mechanism located on the head of the cylinder including an air intake valve adapted to draw 65 air from the atmosphere, and a casing covering said valve mechanism with sides of the casing spaced from the pump and forming with the pump substantially vertical air passages through which air may be drawn 70 to said intake valve.

In testimony whereof I have hereunto set my hand in presence of two subscribing witnesses.

CARL E. L. LIPMAN.
